UNITED STATES PATENT OFFICE.

SAMUEL M. LUCAS, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed September 14, 1926. Serial No. 135,347.

My invention relates to railway traffic controlling apparatus, and particularly to apparatus of the type comprising governing means on a train controlled by energy received from the trackway. More specifically the present invention relates to the trackway portion of such apparatus.

I will describe one form of apparatus embodying my invention, and will then point out the novel features thereof in claims.

The accompanying drawing is a diagrammatic view showing one form of apparatus embodying my invention.

Referring to the drawing, the reference characters 1 and 1^a designate the track rails of a railway along which traffic normally moves in the direction indicated by the arrow. These rails are divided by insulated joints 2 into track sections of which two sections C—D and D—E are shown in the drawing. Each section is provided as usual with a track circuit comprising a battery 4 connected across the rails at the exit end of the section, and a track relay connected across the rails at the entrance end of the section and designated by the reference character R with an exponent corresponding to the location.

Each section is also provided with means for supplying train governing current to the track rails, this means in the form here shown being a transformer designated by the reference character F with an exponent corresponding to the location, and having its secondary 3 connected across the rails at the exit end of the section in series with the track battery 4 and a limiting reactance 5. The primary 6 of transformer F^D is at times supplied with current from a transformer H^D, which in turn is supplied with current from a transformer J^D, the primary of which is constantly supplied with alternating current from a suitable source not shown in the drawing. The circuit for the primary 6 of transformer F^D is from the secondary 7 of transformer H^D, through primary 6, front contact 13 of track relay R^D, front contact 14 of a checking relay X^D to secondary 7. It will be seen, therefore, that train governing current will be supplied to the rails of section D—E when and only when track

relay R^D is energized, that is, when and only when section C—D is unoccupied.

The circuit for primary 8 of transformer H^D includes the secondary 9 of the transformer J^D and a trackway loop L^D. This loop involves two conductors extending parallel with the track rails at the junction between sections C—D and D—E, which conductors extend a short distance into each section. In the form here shown, the loop L^D is constantly energized from the secondary 9 of transformer J^D.

The apparatus thus far described is intended for co-operation with train-carried governing mechanism in such way that when the train is in a section of track which is supplied with train governing current the train may proceed without retardation, but that when the train is in a section of track which is not supplied with train governing current an automatic application of the brakes will be incurred unless the engineer "acknowledges," that is, unless he takes suitable action to indicate that he is alive and alert.

The loop L^D has two functions. First, assuming that section C—D is occupied, so that section D—E is not supplied with train governing current, and assuming that the engineer of the following train has "acknowledged" upon entering section D—E, the train-carried mechanism will be momentarily energized upon passing over the loop L^D, thus requiring a second acknowledgment as soon as the train enters the occupied section C—D. For this reason the loop L^D is referred to as a recurrent acknowledgement loop. Second, it will be noted that the insulated joints 2 at the point D are staggered, so that when sections C—D and D—E are both supplied with train-governing current, a train might receive a momentary stop indication at the point D while the receiving apparatus on the train is passing over the space between joint 2 in rail 1 and joint 2 in rail 1^a. This momentary indication is prevented by the loop L^D, which, of course, supplies train governing current to the receiving apparatus while between these two joints.

If the conductors of the loop L^D should

accidentally make electrical contact with one or both of the track rails, they might transfer track circuit energy from section C—D to section D—E, or vice versa, or they might 5 feed train governing energy into the track rail and thereby falsely energize the receiving apparatus on a train. To prevent this, I have provided means for detecting accidental contact of the loop L^P with a track rail. 10 For this purpose an auxiliary secondary 11 on transformer J^P is connected with the loop L^P and with ground at G^1 , whereas the auxiliary relay X^P is also connected with the loop L^P and with ground at G^2 . A resistance 15 12 is interposed between secondary 11 and the ground G^1 to limit the current from this secondary to a value just sufficient to keep relay X^P energized. In the event of contact between loop L^P and one of the track 20 rails, some of the current from secondary 11 will be shunted around relay X^P , so that this relay will open, it being understood that the electrical connection between the track rail and the ground through the ties and ballast 25 is of reasonably low resistance. In the event of relay X^P opening, contact 14 of this relay will open the primary circuit for transformer F^P and so will discontinue the supply of train governing current to the rails of section D—E. A train entering this section 30 will therefore receive a stop indication.

As here shown, each section is provided with a signal designated by the reference character S , with an exponent corresponding to the location. Referring to signal S^P , the circuit for this signal passes from the terminal B of a suitable source of current, through front contact 15 of relay X^P , front contact 16 of track relay R^P , and the operating mechanism for signal S^P to terminal O of the same source of current. If relay X^P becomes opened, signal S^P will indicate stop, and signal S^P will, of course, indicate caution, thereby giving further indication of the improper condition of the trackway loop L^P .

Although I have herein shown and described only one form of apparatus embodying my invention, it is understood that various changes and modifications may be made therein within the scope of the appended claims without departing from the spirit and scope of my invention.

Having thus described my invention, 55 what I claim is:

1. In combination, a stretch of railway track, means controlled by traffic conditions for supplying train governing energy to the track rails, auxiliary apparatus located 60 in said stretch for supplying governing energy to trains, and means for detecting accidental contact of said auxiliary apparatus with a track rail.

2. In combination, a stretch of railway 65 track, means controlled by traffic conditions

for supplying train governing energy to the track rails, a conductor located in the trackway for also supplying governing energy to trains, and means for preventing the supply of energy from said first source to the track rails in the event of accidental contact of said conductor with a track rail.

3. In combination, a stretch of railway track, means controlled by traffic conditions for supplying train governing energy to the track rails, a conductor located in the trackway for also supplying governing energy to trains, a source of current connected between said conductor and ground, and a relay also connected between said conductor and ground for controlling said supply of energy to the track rails.

4. In combination, a stretch of railway track, a recurrent acknowledgment loop located in the trackway for supplying governing energy to trains, a source of current connected between said loop and ground, a relay also connected between said loop and ground, and a signal controlled by said relay.

5. In combination, a stretch of railway track, means controlled by traffic conditions for supplying train governing energy to the track rails, a conductor located in the trackway for also supplying governing energy to trains, a source of current connected between said conductor and ground, a relay also connected between said conductor and ground, means for controlling said supply of energy to the track rails by said relay, and a signal controlled by said relay.

6. In a system comprising a stretch of railway track divided into sections means for each section controlled by traffic conditions in advance for supplying train governing energy to the rails of the section, an auxiliary conductor located at the junction of two adjacent sections and extending a short distance into each section for momentarily supplying governing energy to trains when the supply of train governing energy to the track rails has been discontinued and for preventing momentary interruption of the supply of energy as a train passes from one section to the other while train governing energy is being supplied to the rails of each section; the combination with the aforementioned instrumentalities of means for detecting accidental contact of said conductor with a track rail.

7. In a system comprising a stretch of railway track divided into sections, means for each section controlled by traffic conditions in advance for supplying train governing energy to the rails of the section, an auxiliary conductor located at the junction of two adjacent sections and extending a short distance into each section for momentarily supplying governing energy to trains when the supply of train governing

energy to the track rails has been discontinued and for preventing momentary interruption of the supply of energy as a train passes from one section to the other while train governing energy is being supplied to the rails of each section; the combination with the aforementioned instrumentalities of a source of current connected between said conductor and ground, a relay also connected between said conductor and ground, and means for controlling the supply of train governing energy to the rear of said two sections by said relay.

8. Railway traffic controlling apparatus comprising recurrent acknowledgment loops

located in the trackway, and means for detecting accidental contact of one of said loops with a track rail.

9. Railway traffic controlling apparatus comprising means for supplying train governing energy to the track rails, a recurrent acknowledgment loop located in the trackway, an auxiliary source of current connected between said loop and ground, and an auxiliary relay connected between said loop and ground for controlling the supply of train governing energy to the track rails.

In testimony whereof I affix my signature.

SAMUEL M. LUCAS.
